UNITED STATES PATENT OFFICE.

ARTHUR E. PEARCE, OF ASHTABULA, OHIO.

DESIGN FOR A TIRE OR TIRE-CASING.

53,858.

Specification for Design.

Patented Sept. 16, 1919.

Application filed May 19, 1919. Serial No. 298,333. Term of patent 14 years.

To all whom it may concern:

Be it known that I, ARTHUR E. PEARCE, a citizen of the United States, and a resident of Ashtabula, county of Ashtabula, State of Ohio, have invented a new, original, and ornamental Design for Tires or Tire-Casings, of which the following is a specification, reference being had to the accompanying drawing, forming part thereof.

In said annexed drawing:—

Figure 1 is a plan view of a tire casing showing my new design; and Figs. 2 and 3 are sections of the same taken on the planes indicated by the lines 2—2 and 3—3 respectively, Fig. 1.

I claim:—

The ornamental design for a tire or tire casing as shown.

Signed by me, this 16th day of May, 1919.
ARTHUR E. PEARCE.
